(57) **CLAIM**

The ornamental design for a baby carriage, as shown and described.

DESCRIPTION

FIG. 1 is a top, front, and right side perspective view for a baby carriage showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a front view of the baby carriage showing in an environment in which it may be used;

FIG. 8 is a rear view thereof;

FIG. 9 is a left side view thereof;

FIG. 10 is a right side view thereof;

FIG. 11 is a top view thereof;

FIG. 12 is a top, front, and right side perspective view thereof;

FIG. 13 is a top, rear, and right side perspective view thereof; and,

FIG. 14 is a top, front, and right side perspective view of the baby carriage showing in another environment in which it may be used.

The translucent white area in FIGS. 7-14 depicts a carry cot and a cup element showing the environment that forms no part of the claimed design.

1 Claim, 14 Drawing Sheets
